United States Patent Office

Des. 229,638

Patented Dec. 18, 1973

229,638

PORTABLE COMBINED HEARTBEAT-MONITOR AND DEFIBRILLATOR UNIT

Harold H. Kawaguchi, Seattle, Wash., assignor to Physio-
Control Corporation, Seattle, Wash.

Filed Jan. 29, 1973, Ser. No. 327,657

Term of patent 14 years

Int. Cl. D24—01

U.S. Cl. D83—1 F

Fig. 1.

Fig. 2.

Fig. 3.

Fig. 4.

Fig. 5.

Fig. 6.

Fig. 7.

Fig. 8.

Fig. 9.

FIG. 1 is a front perspective view of a portable combined heartbeat-monitor and defibrillator unit showing my new design;

FIG. 2 is a front view thereof;

FIG. 3 is a top plan view thereof;

FIG. 4 is a side elevation thereof;

FIG. 5 is a side elevation with the case closure in a fully opened position;

FIG. 6 is a top plan view with the case closure in a closed position;

FIG. 7 is a side elevation thereof;

FIG. 8 is a front elevation thereof; and

FIG. 9 is a rear elevation thereof.

I claim:

The ornamental design for a portable combined heartbeat-monitor and defibrillator unit, as shown.
